UNITED STATES PATENT OFFICE.

GEORGE H. DEAN, OF NORWOOD, RHODE ISLAND.

SUCTION FILTER.

Application filed March 6, 1928. Serial No. 259,444.

My invention relates to suction filters of the porous type.

The essential objects of my invention are to subject the entire porous wall 5 of the filter to suction, and to evenly distribute the suction throughout its entire length, whereby the clogging of the pores is materially delayed; to lessen the amount of vacuum required to be produced by the 10 pump or other suction apparatus; to prevent the clogging of the inlets of the suction pipe; to prevent entrance of the sand through the suction pipe into the suction device; to enable the facile substitution of any broken 15 part of the filter; to facilitate the assemblage of the filter parts; and to attain these ends in a simple and inexpensive manner.

To the above ends essentially my invention consists in such parts and in such combinations of parts as fall within the scope of the appended claims.

In the accompanying drawings which form a part of this specification

Figure 1 is a plan view of my filter,
25 Figure 2, a vertical section of the same,
Figure 3, a transverse section on line 3—3 of Figure 2, and

Figure 4, a sectional view of a well or cistern shown in side elevation with my 30 device mounted therein.

My filter in its preferred embodiment comprises a cylindrical side 7 of any well known porous material suitable for this purpose, such as a hardened mixture of sand and 35 cement. The wall is of substantial thickness with smooth end faces.

A circular metallic base plate 9 of a diameter equal to that of the exterior of the side has a peripheral upturned flange 10 adapted to embrace the lower end of the side 40

7. The base in this instance has a central cylindrical projection 12 integral with its upper face registering in the lower end of a section 13 of the suction pipe, to which projection the section is united by welding or otherwise so as to insure a rigid connection. The pipe section is provided at its upper end with an external thread 14 and near its bottom end with diametrically oppositely 45 disposed inlet openings 15. Integral with the base 9 is a substantially cylindrical baffle plate 17 concentric with the suction pipe section 13 and spaced from both the latter and the side 7. Its exterior face is preferably slightly tapering upwardly and inward-

ly presenting a slightly trunco conical appearance, as at 18. It is essential for the best results that the height of the baffle plate not extend above half the height of the pipe section 13 or the side 7.

A circular metallic top plate 20 adapted to rest upon the top face of the side 7 has a depending peripheral flange 21 adapted to embrace the latter. Upon the central portion of its upper face the plate 20 has a polygonal elevation or integral nut portion 23 to accommodate a wrench. The center of this plate and elevation is provided with a hole 24 having an internal thread 25 adapted to engage the thread 14 upon the pipe section 13.

In assembling the described parts into a complete suction filter 27 the side 7 is placed upon the base plate 9. The combined top and clamping plate is next applied to the 75 pipe section 13 above the side 7 and, by a wrench applied to the elevation 23, screwed tightly down, thereby clamping the three members into secure interengagement. When thus clamped it will be found that 80 there results a large closed cylindrical central chamber 29 divided in its lower portion by the baffle plate into two substantially annular sub chambers 30 and 31, exterior and interior respectively of the baffle plate.

After the filter has been assembled as above described it may be connected with a longer suction pipe section 33 by a coupling sleeve 35 or otherwise. The pipe section 33 is herein shown connected with a suction 90 mechanism or device 37 which is in this instance a pump. The filter depends in this instance near the bottom of a well or cistern 39 closed by a cover 40 which supports the pump.

In operation the water is, by suction through the pipe 13, drawn from the exterior of the filter with even force through the side 7 from top to bottom, as indicated by the arrows, and thence down through the sub chamber 31 and the openings 15 into the pipe section, and upwardly therethrough. The prolongation of the baffle plate to a point approximately midway the height of the filter is to increase the resistance to the ingress of water as the bottom of the filter is approached to correspond with the increase of pressure, with the result that the ingress of water through the porous side of the filter is distributed more evenly throughout the 100 105 110

length thereof. The presence of the abutment is found to lessen the amount of vacuum required to be produced by the suction device, and lessening the vacuum also results 5 in causing any incoming sand from the filter side to more readily fall into the sub chamber 30 instead of into the chamber 31. The baffle plate by thus walling off any incoming sediment not only causes it to be deposited 10 in the chamber 30 but thereby prevents its clogging the openings 15 or ultimately entering and injuring the pump.

It will be noted that the utilization of the 15 top plate 20 as a clamp affords a facile means of assembling and disassembling the constituent parts of the filter for the removal of sand accumulation or replacing broken parts.

It will be further noted that the rigid connection of the suction pipe 13 with the bottom plate stiffens the entire filter structure to a remarkable degree.

Furthermore the parts of the structure are reduced to a minimum.

25 I claim:

1. In a suction filter, a base plate, a tubular porous side upon the plate, a suction pipe fixed at its lower end to the center of the plate concentric with the side and provided 30 with inlets near its lower end, a baffle plate upon the base plate surrounding the pipe and spaced from the pipe and side and extended up a large portion of the height of the filter wall, and a plate upon the top 35 of the side engaging the pipe.

2. In a suction filter, a base plate, a suction pipe fixed at one end to the center of the base provided with inlets, a tubular porous side resting upon the plate exterior of the

pipe, a baffle plate integral with the base 40 plate between the pipe and side and extended up a large portion of the height of the filter wall and surrounding the inlets and a clamping plate provided with a central hole to receive the pipe and detachably 45 engaging the pipe resting upon the side.

3. In a suction filter, a base plate, a suction pipe fixed at its lower end to the plate and provided adjacent the plate with inlets, and provided with a thread, a tubular porous 50 side resting upon the plate spaced from the pipe and concentric therewith, a substantially cylindrical baffle plate integral with the base plate and extended up a large portion of the height of the filter wall, a clamping plate resting upon the side, and provided with a central hole to receive the pipe therethrough and with a thread in the hole 55 engaging the thread upon the pipe.

4. A suction filter comprising a base plate, a top plate, the base plate having rigid therewith an upwardly extending baffle plate and extended up a large portion of the height of the filter wall, a porous surrounding 60 wall, a suction pipe extended upward 65 beyond the baffle plate and communicating near its lower end with the space enclosed by said baffle plate, a top plate through which the upper end of the suction pipe extends, the lower end of said pipe being 70 mounted within the space enclosed by the baffle plate, and a detachable connection between the upper end of the pipe and top plate.

In testimony whereof I have affixed my 75 signature.

GEORGE H. DEAN.
